DESIGN FOR A CHILD'S DRESS

Frank J. Eppolito, New York, N. Y.

Application September 16, 1939, Serial No. 87,247

Term of patent 3½ years

To all whom it may concern:

Be it known that I, Frank J. Eppolito, a citizen of the United States of America, residing in New York city, in the Borough of Manhattan, county and State of New York, have invented a new, original, and ornamental Design for a Child's Dress, of which the following is a specification, reference being had to the accompanying drawing, forming part thereof, wherein,

I claim:

The ornamental design for a child's dress, substantially as shown.

FRANK J. EPPOLITO.
